UNITED STATES PATENT OFFICE.

WILLIAM F. HEFFNER, OF BENTON HARBOR, MICHIGAN, ASSIGNOR OF ONE-FOURTH TO HENRY SPATZ AND ONE-FOURTH TO JOHN L. TAYLOR, BOTH OF BENTON HARBOR, MICHIGAN.

CLASP FOR LOOSE-LEAF BINDERS.

No. 805,794.

Specification of Letters Patent.

Patented Nov. 28, 1905.

Application filed June 22, 1905. Serial No. 266,483.

To all whom it may concern:

Be it known that I, WILLIAM F. HEFFNER, a citizen of the United States, residing at Benton Harbor, in the county of Berrien and State 5 of Michigan, have invented certain new and useful Improvements in Clasps for Loose-Leaf Binders; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to new and useful improvements in loose-leaf clasps, and is adapted mainly for use in connection with books, files, and ledgers in which the leaves are removable for the replacement of new ones; and the 20 object of the said invention is to provide a device which is easily and cheaply manufactured and at the same time simple in construction.

To these ends and to such others as the invention may pertain the same comprises, further, 25 the various details of construction, arrangement, and combination of parts and features, which will be hereinafter more fully set forth and described and then pointed out in the appended claim.

30 The invention is illustrated in the accompanying drawings, which, with the letters of reference marked thereon, form a part of this application, and in which drawings similar letters of reference indicate like parts in the 35 views, in which—

Figure 1 is a perspective view of a loose-leaf book, showing the invention applied thereto. Fig. 2 is a sectional view on line 2 2 of Fig. 1. Fig. 3 is a perspective view of the device removed, and Fig. 4 is a sectional view 40 on line 4 4 of Fig. 2.

Reference now being had to the details of the drawings by letter, A designates the stiffened leather backing of a loose-leaf book, and 45 B is a sheet of linen paper or any other suitable material pasted on the inside faces of the stiffened back to give a finished appearance to the book.

C designates a strip of pasteboard, which 50 is placed in the middle of the backing, and D is the base of the clasp, which is made of metal or any other suitable material, the ends

of which being made thin are bent under the said pasteboard, as at E, to securely hold said base to the pasteboard. To securely hold said 55 base of the clasp and pasteboard in position, a piece of linen F is provided, which is shown in Fig. 1 in dotted lines and in Fig. 2 in section. Said piece F has elongated apertures G, which are passed down over the arch-formed clasps. Thus it will be understood how the base of the clasps and the pasteboard are held in place. The clasp is made in two 60 separate pieces, and when the same is closed it has the appearance of an arch. The two 65 separate pieces are designated by the letters H and I. The lower portion of the piece H is bent at right angles to the vertical portion of said piece, as at J, and is provided with laterally-disposed lugs K substantially at the 70 bend of the said bent portion, said lugs having a pivotal engagement with notches L, formed in the vertically-disposed side flanges M. N designates an elongated aperture adapted to receive the end of a spring O, as 75 shown in Fig. 3 of the drawings. The opposite piece I of the clasp, which is held rigid, is also bent at its lower portion and held under the body portion of the spring O by means of oppositely-disposed ears Q, which are bent 80 over the said body portion of the spring and the bent portion of the piece I, as shown clearly in Figs. 3 and 4. To prevent lateral displacement of the piece H when in closed position, the piece I is provided with a semi-circular projection R, which is engaged by a 85 similar shaped recess S in the piece H, as will be clearly seen in Figs. 2 and 3 of the drawings.

To operate the device, it is necessary to 90 swing the piece H upon its pivot, then to insert the piece I through the elongated openings formed in the loose sheets A' and allow the piece H to snap together, as will be clearly understood by referring to the drawings. 95

Having thus fully described my invention, what I claim as new, and desire to secure by Letters Patent, is—

A clasp for loose-leaf binders comprising a plate adapted for attachment to the cover of 100 a binder, said plate having longitudinal flanges upon its opposite edges, lugs projecting from said flanges at positions opposite each other, a clasp member I having its base passing

underneath said lugs, a spring resting upon the base of said clasp-piece and engaged by said lugs which are bent toward each other, a pivotal clasp-section having outwardly-extending lugs which are journaled in recesses in said flanges, a portion of said pivotal clasp-section having an aperture therein through which the free end of said spring passes, a portion of the pivotal clasp-section being bent

at an angle and positioned underneath said spring, as shown and described.

In testimony whereof I hereunto affix my signature in presence of two witnesses.

WILLIAM F. HEFFNER.
